UNITED STATES PATENT OFFICE

2,459,800

SAWMILL CONSTRUCTION

Ernest E. Esgate, Coeur d'Alene, Idaho

Application May 16, 1947, Serial No. 748,640

1 Claim. (Cl. 248—23)

(Granted under the act of March 3, 1883, as amended April 30, 1928; 370 O. G. 757)

1

The invention described herein may be manufactured and used by or for the Government for governmental purposes, without payment to me of any royalty thereon.

This invention relates to a platform mounting for portable sawmills and, more particularly, is concerned with such mountings provided for increased portability and simplification of installation and operation.

It is the general object of my invention to provide a new and improved mounting suitable for installation on a variety of conventional high capacity portable sawmills, the platform-mounted mill being relatively inexpensive to manufacture, long-lived and capable of producing large volumes of sawed lumber with the employment of a limited number of skilled workmen.

Another object of my invention is the provision of a means of assembling the components of a high capacity portable sawmill into a compact and highly mobile unit at the factory, to eliminate many time-consuming operations and to obviate the necessity for dismantling and reassembling the components each time the high capacity portable sawmill is moved from the scene of one operation to another.

Another object of my invention is to provide for a considerable reduction in the skill required to install and maintain a high capacity portable sawmill for operation, through the provision for assembly of the components at the factory, to require only minor operating adjustments at the scene of operations.

Another object of my invention is to provide for a platform mounting that may be readily increased in width without sacrifice of rigidity and that is not limited to special types of sawmill equipment or to special means of transport, the said platform mounting being suitable for transport on any conventional logging truck and trailer combination or similar vehicle, and also suitable for transport on wheels attached to the framework when towed by a conventional truck, tractor, or other vehicle.

Another object of my invention is to provide for increased productive capacity and improved accuracy of performance in portable sawmills through the design of a platform mounting that increases the rigidity of the operating base and maintains the relation between the planes in which components operate.

The foregoing objects of my invention, and other objects thereof which will become apparent as the description proceeds, are achieved by the provision of a platform mounting of the type

or types illustrated, in accordance with my invention, in the accompanying drawings, wherein:

Fig. 1 is a side elevation of a platform-mounted high capacity portable sawmill as installed for operation;

Fig. 2 is a top plan view of the platform shown in Fig. 1;

Fig. 3 is a side elevation of a unit loaded for transport on a conventional logging truck-trailer combination;

Fig. 4 is a top plan view of an end portion of the base, showing a hinged end section and portions of the expanded metal flooring;

Fig. 5 is a perspective view of the portion of the base shown in Fig. 4;

Fig. 6 is a sectional elevation showing the construction of one of the jacks used in elevating the base;

Fig. 7 is an elevation showing a portion of the central section of the base, and a hinged end section connected therewith;

Fig. 8 is a sectionized elevation taken on the line 8—8 of Figure 4;

Fig. 9 is a sectionized elevation taken on the line 9—9 of Figure 4;

Fig. 10 is a sectionized elevation showing the mounted location of the saw, motor and log carriage tracks, the view being taken on the line 10—10 of Figure 1;

Fig. 11 is a vertical cross-sectional view similar to that shown in Fig. 10, but showing the platform after widening the same by the insertion of the central expansion member, to adapt it for mounting the largest type of conventional portable sawmill;

Fig. 12 is a perspective view showing a central end portion of the frame with spacing member inserted therein.

Referring to Fig. 1 of the drawings, it will be noted that the base 10 is composed of three sections or units comprising a central section 11 and two end sections 12 and 13 which are hingedly connected to the central section 11 by hinge members 14 and 15, and which may be folded up

to overlap the central section as shown in Fig. 3. The units 11, 12 and 13 are composed of a framework formed of structural members comprising upper longitudinal beams 16, 17 and 16', 17', lower longitudinal beams 18, 19, 20 and 18', 19', 20', upper transverse elements 21 and 21', lower transverse elements 22 and 22', support elements 23 and 23', longitudinal bracing elements 24, 25, 26 and 24', 25', 26', central bracing elements 28 and transverse bracing elements 27 and 27'. The upper longitudinal and transverse elements form

an upper deck which is partially covered by expanded sheet metal 50. The lower longitudinal and transverse elements lie in a plane parallel to the upper deck. Both the upper and lower longitudinal members are not only utilized as frame members of the mobile base but as support elements for the saw mounting 29, the motor 30, and the tracks 31 on which is mounted the longitudinally movable carriage 32. It will be noted in Fig. 3 that when the end sections 12 and 13 are folded back upon the upper surface of the central section 11, the carriage is locked in place, and that the base is so constructed that it may be elevated by lifting it from either end, or by lifting the entire unit from the center thereof.

The saw frame assemblies 51 and 52 are made as an integral part of the platform assembly to support the conventional saw mechanisms 53 and 54.

Provision is also made in the design to include an electric motor as a part of the assembly, but the saws may also be operated by connecting the same to a counter shaft to transmit power from an outside source.

Both the central portion or section 11 of the base 10 and the end sections 12 and 13 are provided with supporting jacks 33 which are connected to the upper transverse members 21, 21' and the lower transverse members 22, 22'. The jacks which are of the conventional trench brace design consist of a screw member 42 threadably mounted within a tubing support member 43 and are provided with base plates 35 which are retractable within the base 10, between the lower longitudinal members 18, 19 and 18', 19'. When the jacks are thus retracted, the base presents a non-obstructed lower surface that will permit passage thereof over a roller for loading.

It will be noted from the end elevation shown in Figs. 5 and 9 that the frame is braced centrally by transverse bracing members 27 and 27' and that the entire frame is made up of separable halves joined centrally by bolting the upper longitudinal members 17 and 17', and lower longitudinal members 20 and 20' together, and uniting the lower transverse members 22, 22' by a lock bar 34 which is bolted to each of these members.

The transverse sections are formed of two units, one of which comprises upper and lower transverse horizontal members 21 and 22, the transverse braces 27 and the outer support members 23, and a symmetrically formed unit including the upper and lower transverse horizontal members 21' and 22', the transverse braces 27' and the outer support members 23'. In each section are mounted jacks 33 at locations where they will not only form a stable support for the base but also support the apparatus mounted on the base without causing excessive strain in any particular member of the frame. This is accomplished by locating the jacks 33 as near as possible to the center of gravity of the supported loads and at the same time far enough from the longitudinal center of the base to effect stable support for the entire structure.

Since each side of the frame, on either side

of the longitudinal center, is a complete structure or unit, these structures may be separated by a spacing unit 38 in order to widen the frame or base to accommodate larger logs, with which it may be necessary to use two saws, as indicated by the numerals 39 and 40 in Fig. 11. The separation of the frame centrally into two units also facilitates processing the same for export purposes.

- 10 The spacing unit 38 is composed of upper longitudinal members 45, 45', upper transverse member 46, lower longitudinal members 47, 47', lower transverse member 48 and extension strips 49. The upper transverse and longitudinal members, and lower transverse and longitudinal members of the spacing unit 38 are connected by jacks 33. Thus, when the platform is widened the jacks of the spacing unit or insert 38 provide central supports for the widened span.
- 15 20 The insertion of the spacing unit 38 provides additional width in the overall structure that may be utilized to increase the width of the carriage 32, the length of the saw mandrel 54' or of either or both.
- 25 30 In the illustrations the frame is shown as being composed of structural members of the solid type such as angles and channel bars, but other shapes, especially tubing, may be used to suit the purpose for which the device is especially designed. If an extremely light structure is desired tubing would be the ideal structural shape to use.

Having thus described my invention, what I claim and wish to secure by Letters Patent is:

- 35 A platform adapted for the mounting of conventional sawmill units, and comprising a trussed frame structure including a central section and end sections hingedly connected thereto and foldable upon said central section, said sections being formed in symmetrical separable halves connected together along the longitudinal center line, and an insert adapted to be placed intermediate said symmetrical half sections to widen said frame, said frame and said insert being composed of upper and lower longitudinal and transverse members, and spacing members, said spacing members including jacks connected to said upper and lower transverse members, positioned laterally from the longitudinal center of said mounting a distance sufficient to effect stability thereof and to support the loads thereon at least substantially beneath their centers of gravity, and base plates operatively connected to said jacks adapted to be retracted within said trussed structure between said lower longitudinal members.
